CLAIM

The ornamental design for a cut resistant glove with elastomeric straps, as shown and described.

DESCRIPTION

FIG. 1 is a perspective view of a cut resistant glove with elastomeric straps showing my new design, the glove having a plurality of vertical stiffeners and snap-fastened elastomeric straps (further depicted in FIGS. 20-29), and with the elastomeric straps being shown in a relaxed state;
 FIG. 2 is a front elevational view thereof;
 FIG. 3 is a rear elevational view thereof;
 FIG. 4 is a right side elevational view thereof;

FIG. 5 is a left side elevational view thereof;
 FIG. 6 is a bottom plan view thereof;
 FIG. 7 is a top plan view thereof;
 FIG. 8 is a front elevational view thereof showing the elastomeric straps in a stretched state;
 FIG. 9 is a top plan view thereof;
 FIG. 10 is a bottom plan view thereof;
 FIG. 11 is an enlarged view of the mesh taken from FIG. 1;
 FIG. 12 is a perspective view of a second embodiment of a cut resistant glove with elastomeric straps, the second embodiment being identical to the first embodiment except for having a lower cuff height and not including vertical stiffeners;
 FIG. 13 is a front elevational view thereof;
 FIG. 14 is a left elevational view thereof;
 FIG. 15 is an enlarged view of the mesh taken from FIG. 12;
 FIG. 16 is a perspective view of the embodiment of FIG. 12 shown with the buckle-fastened elastomeric straps further depicted in FIGS. 30-36;
 FIG. 17 is a front elevational view thereof;
 FIG. 18 is a left side elevational view thereof;
 FIG. 19 is an enlarged view of the mesh taken from FIG. 16;
 FIG. 20 is a perspective view of the snap-fastened elastomeric strap shown separately from a glove for ease of illustration, the elastomeric strap being in an unthreaded, snapped state;
 FIG. 21 is a front elevational view thereof;
 FIG. 22 is a rear elevational view thereof;
 FIG. 23 is a bottom plan view thereof;
 FIG. 24 is a top plan view thereof;
 FIG. 25 is a right side elevational view thereof;
 FIG. 26 is a left side elevational view thereof;
 FIG. 27 is a top plan view thereof, the snap-fastened elastomeric strap being in a threaded, snapped state;
 FIG. 28 is a left side elevational view thereof;
 FIG. 29 is a right side elevational view thereof;
 FIG. 30 is a perspective view of the buckle-fastened elastomeric strap shown separately from a glove for ease of illustration, the elastomeric strap being in an unthreaded state;
 FIG. 31 is a front elevational view thereof;
 FIG. 32 is a rear elevational view thereof;
 FIG. 33 is a bottom elevational view thereof;
 FIG. 34 is a top plan view thereof;
 FIG. 35 is a right side elevational view thereof; and,
 FIG. 36 is a left side elevational view thereof.
 The broken lines in the drawings illustrate features of the article of manufacture that form no part of the claimed design. No claim is made to any feature located between the symbolic break boundary lines shown in FIGS. 17-21 and 27-31. The mesh, although shown intermittently in the drawings for ease of illustration, is understood to continue throughout the glove. The stippling shown in the drawings serve to indicate that the strap is made of a smooth, elastomeric material.
